UNITED STATES PATENT OFFICE.

JOHN F. CLASS, OF PLEASANT HILL, OHIO.

RAILWAY TURN-TABLE.

SPECIFICATION forming part of Letters Patent No. 352,970, dated November 23, 1886.

Application filed July 28, 1886. Serial No. 209,319. (No model.)

To all whom it may concern:

Be it known that I, JOHN F. CLASS, a citizen of the United States, residing at Pleasant Hill, in the county of Miami and State of Ohio, have 5 invented certain new and useful Improvements in Railway Turn-Tables; and I do hereby declare the following to be a full, clear, and exact description of the invention, such as will enable others skilled in the art to which it applies to make and use the same.

My invention relates to turn-tables for turning or shifting railroad engines and cars.

The leading object of the invention is to produce a turn-table which will, by virtue of the 15 weight of the engine, truck, or car run upon it, automatically revolve and turn said engine, truck, or car to any desired track, and when the weight is removed by running the engine, truck, or car off the table will automatically 20 restore the turn-table to its original position. The power to produce these results is stored by the weight of the engine, truck, or car when run upon the table.

The invention also includes means for locking 25 the automatic returning or restoring means, so that its power is given off only as desired by the operator.

It also embodies means for holding the turn-table in any desired position in the pit or bed 30 in which it is placed, whereby the automatic action is held in abeyance until such time as the operator may desire it to be exercised.

It also includes means whereby the action of the springs is suspended, so that a second burden or load can be placed upon the table and 35 revolved by power stored by the preceding load.

Many minor points of action and advantage 40 will appear in the following detailed description.

The accompanying drawings illustrate what I consider the best means for carrying my invention into practice.

Figure 1 is a side elevation; Fig. 2, a vertical section; Fig. 3, a transverse sectional view on line $x-x$ of Fig. 1, looking toward the right. Figs. 4 and 5 are detail views of the locking-levers.

Similar letters of reference indicate corresponding parts in all the figures where they occur.

A is the circular track or support on which the wheels of the turn-table move. B B represent such wheels placed under each end of the turn-table.

C C are the longitudinal framing pieces of the turn-table, in which the hangers C' C' are placed to support wheels B B. A cross-piece, C^x, placed under the framing-pieces C C at about mid-length, bears small rollers C^{xx} C^{xx}, 60 which rest and revolve upon a table or platform, D, held upon posts d d d d. Beneath the table D is a plate, E, which has a worm, E'. The table E works freely up and down over the posts d d, and springs E^x tend to keep 65 it elevated. The springs E^x are coiled around the posts d d, and are powerful springs, sufficient by their recoil to turn the turn-table with an engine or truck upon it. A plunger, F, with horizontal roller extensions f f, works in 70 the worm E', the extensions f f bearing upon the inclines of the worm. This plunger is held at the top in a cross portion or head, G^x, of the centrally-pivoted track G. Arms g g, secured to the sides of this head G^x, extend down 75 through extensions or ears on the cross-piece C^x, and have coiled springs g' g' around them, resting between the upper and lower cross-pieces C^x and G^x.

The track-rails G are pivoted at their inner 80 ends to the cross-head G^x, and the center portion of them is raised and lowered with said cross-head, thus causing the track to assume the position of a double incline when the springs g' g' recoil. The head of the plunger 85 F is provided with a clutch, as shown at F^x, and a corresponding clutch portion, G^{xx}, held in cross-head G^x, with liberty to be moved vertically, locks and operates upon the clutch head F^x, and prevents it from revolving, thereby causing it, when depressed, to 90 depress the worm E' and table E, and compress the springs E^x, thus storing power in said springs, and causing their recoil to revolve the turn-table by the pressure of the 95 worm upon the plunger.

I provide a locking lever or levers, H, operated by a hand-lever, H', which can be engaged with ears or projections g² g² on cross-piece G^x, and hold the track down in a horizontal position, and prevent the recoil of springs g' g', until such time as the operator 100

desires to permit said springs to recoil and turn the turn-table backward. I also provide a locking projection, I, which extends beyond the end of the turn-table frame, and engages with openings cut in the sides of the pit to hold the turn-table at any point. This projection is kept in normal position for engagement with the openings in the sides of the pit by a spring, i, and is operated by a hand-lever, I', to withdraw it from such engagement. The end of the projection is rounded, so as to work easily in and out of the openings. Both hand-levers H' and I' are pivoted to the ends of the cross-piece C^x, and extend up beside and above the track, so that they can be taken hold of by the engineer or other person on the engine, truck, or car. The portion G^{xx} of the clutch may be provided with a lever, by which it can be raised or lowered to engage or disengage the clutch-head F^x of the plunger F. The engagement of these parts not only holds the plunger circularly fixed and insures the rotation of the turn-table when it is released, but it also prevents the elevation of the worm when the turn-table is locked in the pit and the burden or load removed from the turn-table. The unused power stored in the lower set of springs will be retained and can be used to turn the table with another load upon it. The track-rails, which are pivoted in the head G^x, are carried at their outer ends upon trucks or wheels J, which run upon the frame-pieces C C. The track-rails have slots, which rest over pins j on the trucks J, which give freedom of movement to the tracks, and prevent the tracks breaking loose from the trucks. The trucks J are connected to the cross-head by braces J^x, which cause said trucks to be moved back and forth upon the pieces C C without straining the connection between the rails and trucks. The braces J^x have projections j^x, which rest under the cross-ties of the track, and not only help to stiffen the track, but also insure the proper movement of the trucks. The arms g g not only serve as holders for the springs, but also cause the track to be held steady.

Having thus described my invention, what I desire to claim and secure by Letters Patent is—

1. A turn-table having springs compressed by the weight of the engine, truck, or car to turn the turn-table with the burden upon it, and a second set of springs also compressed by the weight of the engine, truck, or car for re-

storing the table to its normal position when the burden is removed.

2. A turn-table having a track centrally pivoted to a cross-head and springs on the side to elevate the central portion of the track when the burden is removed.

3. In a turn-table, the combination, with the worm and the plunger working therein, of the centrally-pivoted track and springs for elevating its central portion, as set forth.

4. In a turn-table, the combination, with the worm, of the plunger working therein, centrally-pivoted track having the head of the plunger held within it, and springs, as described, for raising the center of the track, as set forth.

5. In a turn-table, the combination, with the worm, of the plunger working therein having a clutch on its upper end to be operated as described, a centrally hinged or pivoted track, and springs for elevating the same.

6. In a turn-table, the combination, with the worm, plunger, centrally-pivoted track, and springs for elevating it, of a locking-lever for holding the track down.

7. In a turn-table, the combination of the worm mounted upon springs, the plunger working in said worm and having the clutch at its top, substantially as and for the purpose set forth.

8. In a turn-table, the combination, with the worm, plate to which it is attached, the posts on which the plate works up and down, and springs surrounding said posts, of the plunger working in the worm and connected to a depressible track above, as set forth.

9. The combination of the centrally-pivoted depressible track having arms extending downward on each side and working in openings in ears or projections on the framing.

10. The combination, with the centrally-pivoted track and means, as described, for raising it, of the trucks J, on which the ends of track are carried.

11. The combination, with the centrally hinged or pivoted track, of the trucks J and braces J^x, as set forth.

12. The combination of the turn-table, having means for automatically rotating it, and a spring-actuated bolt for engaging the sides of the pit in which the table revolves.

In testimony whereof I affix my signature in presence of two witnesses.
